(57) **CLAIM**

The ornamental design for a communication conference device, as shown and described.

DESCRIPTION

FIG. 1 is a front view of a communication conference device showing our new design in a position for use with the upper member inclined to the base;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is another top view thereof, showing an alternate rotated position for use wherein the upper member is parallel to the base;

FIG. 8 is a perspective view thereof;

FIG. 9 is another top view thereof, showing another alternate rotated position for use wherein the upper member is perpendicular to the base; and,

FIG. 10 is a perspective view thereof.

The broken lines depict portions of the communication conference device that form no part of the claimed design. All surfaces shown between the broken and solid lines and the broken lines themselves form no part of the claimed design.

1 Claim, 10 Drawing Sheets
